CLAIM

The ornamental design of a land clearing tool interface, as shown and described.

DESCRIPTION

FIG. 1 is a front, right, perspective view of a land clearing tool interface;

FIG. 2 is a rear, left perspective view thereof;

FIG. 3 is a top view thereof;

FIG. 4 is a right side view thereof, with a left side view being a mirror image of FIG. 4;

FIG. 5 is a bottom view thereof; and,

FIG. 6 is a front view thereof.

(Continued)

CPC E02F 9/2833; E02F 9/2841; E02F 9/28

See application file for complete search history.

The broken line showing in the drawings is included for the purpose of illustrating portions of the land clearing tool interface and forms no part of the claimed design.
